ADOLF SCHOLZ, OF NEW YORK, N. Y.

PRESSURE-REGULATOR FOR STEAM-BOILERS.

1,372,200.

Specification of Letters Patent. Patented Mar. 22, 1921.

Application filed November 5, 1919. Serial No. 335,799.

To all whom it may concern:

Be it known that I, ADOLF SCHOLZ, a citizen of the United States, and resident of the city of New York, in the county of New York and State of New York, have invented a certain new and useful Pressure-Regulator for Steam-Boilers, of which the following is a specification.

This invention relates to devices that are utilized for automatically regulating the pressure of steam boilers, and particularly to the type of regulator which is operated by the pressure of the steam generated by the boiler in connection with which it is installed, and the damper and air doors of which it controls to cause generation of the steam at a uniform pressure.

The principal object of my invention is to provide a simple, inexpensive, efficiently operating and improved automatic pressure regulator for steam boilers, of the above stated type, which may be installed conveniently and economically, and which when in operation may at all times be readily, rapidly, and conveniently set to accurately control the damper and air doors of the boiler for generating the steam at any predetermined pressure desired.

Other objects and advantages will herein-after appear.

In the accompanying drawings,—

Figure 1 shows an elevation of the pressure regulator, partly in section.

Fig. 2 is a plan view of the regulator shown in Fig. 1.

Fig. 3 is a side elevation of the regulator, on a reduced scale.

The cylinder 1 of the regulator is closed at the lower end thereof by a head 2 and at its upper end by a head 3, which heads are secured in place by bolts 4 in the usual manner. A piston 5 located in the cylinder 1 is slidable upwardly and downwardly therein and is secured to a rod 6, which extends upwardly therefrom and passes through a centrally located hub 7 that forms part of the head 3 and serves as a guide for the rod. A pipe 8 passes through the lower head 2 to which it is secured and from which it extends over to the steam portion of the boiler, not shown, in connection with which the regulator is installed, whereby the steam from the boiler enters the lower part of the interior of the cylinder 1, between the piston 5 and the head 3. Above the head 3 is located a sleeve 9 which embraces the rod 6

and is therefore adjustable upwardly and downwardly therealong, and a set screw 10 passes through the sleeve 9 and serves to secure said sleeve to the rod at any position to which it may be adjusted. The rod 6 passes through a central opening 11 formed in a flat-metal cross-bar 12, whereby said bar is slidable upwardly and downwardly along the rod, and a spring 13 is located between the bar 12 and the sleeve 9 and is coiled around said rod. Two bolts 14 secured to the head 3 extend therefrom upwardly and pass through openings formed in the extremities of the cross-bar 12, and thumb-nuts 15 thread over said bolts against the top surface of said cross-bar. A rock-shaft 16 is mounted in a pair of bearings 17 secured to said head by means of screws 18. Said shaft carries a lever 19 keyed thereupon between the bearings 17 and is provided with a pin 20 that enters a forked extension 21 formed upon the sleeve 9. To the extremity 22 of the rock-shaft 16 is secured an arm 23 which is pivotally joined to a series of links 24 that is in turn joined to the ash-pit doors of the boiler, while to the opposite extremity 25 of said shaft is secured a similar arm 26, which is pivotally joined to a series of links 27 that is in turn joined to the damper of the boiler. A blow out valve 28 serves to discharge any steam that may accumulate on the upper side of the piston 5 through leakage.

In the operation of this pressure regulator, steam is first generated in the boiler until it is brought up to a certain desired pressure, as can be ascertained from the pressure gage of the boiler. Steam at said predetermined pressure thereupon enters the cylinder 1 through the pipe 8 and forces the piston 5 upwardly. The thumb-screws 15 are then threaded downwardly to force down the bar 12 and thereby compress the spring 13 against the sleeve 9 secured to piston-rod 6, until the spring exerts a downward pressure upon the rod 6 equal to the upward pressure exerted by the steam-pressed piston 5. Under this condition the spring and steam pressures upon the opposite sides of the piston 5 equalize and tend to maintain said piston at about midway between the cylinder heads 2, 3, while the series of links 24, 27 are so connected to the ash-pit doors and damper respectively that they maintain these partially open, so as to create just sufficient draft to heat the furnace to a tempera-

ture capable of generating steam at the desired predetermined pressure.

Should the steam pressure in the boiler now mount higher than required, it would cause the piston 5 to rise and thereby move the rod 6 with its secured sleeve 9 upwardly contrary to the pressure of spring 13, and the sleeve 9 moving upwardly would swing the lever 19, through the slideable and pivoted coaction of the pin 20 of the latter with the forked end 21 of the former, and rock the shaft 16, which would cause the arms 23, 26 to swing in a clockwise direction, as viewed in the drawing. Said movement of the arms 23, 26 would thereupon be transmitted to the links 24, 27 which would actuate the ash-pit doors and damper to close fully or partially more, to shut off or reduce the draft, in which manner the temperature of the furnace would be lowered and the steam pressure consequently reduced until it would be restored to that normally required. Should the steam pressure in the boiler thereafter drop below the amount required, the opposite operation would take place and the piston 5 would sink under exertion of the spring 13, and the sleeve 9 would thereupon swing the lever 19 and rock the shaft 16 oppositely and swing the arms 23, 26 in a counter-clockwise direction. The movement of said arms would then actuate the links 24, 27 to open the ash-pit doors and damper more fully, increase the draft and temperature of the furnace, and consequently raise the steam pressure in the boiler to the predetermined extent required. In this manner the pressure regulator will operate continually while the boiler is in operation to automatically open and close the air-doors and damper and thereby maintain the steam in the boiler at the uniform desired pressure. In case it should be desired to operate the boiler to generate a higher or lower steam pressure the regulator may be reset for such purpose in the above described manner, *i.e.*, the steam may be raised to the pressure required as indicated by the gage, and the nuts 15 may be threaded to adjust the power spring 13 to just balance the upward pressure exerted against the piston 5 by the steam, after which the regulator will continue to function under its reset condition and maintain the new uniform pressure desired.

If any dislocation should take place in the link connections 24, 27 which would tend to lengthen or shorten the connection between the regulator and the ash-pit doors and damper, the same may be very readily compensated by unthreading the set-screws 18^a and resetting the arms 24, 26 upon rock-shaft 16 to alter their angularity, and then retightening said screws. Further compensation for such purpose may be made by unthreading the set-screws 10 and therewith

adjusting the position of the sleeve 9 along the rod 6 to a different elevation, to thereby alter the angularity of swinging of the arms 23, 26. It will be evident that with the aforesaid adjustments the pressure regulator may be rapidly and conveniently set up for the accurate and efficient operation of the air doors and damper both in the installation of the regulator and for any future contingencies that may arise that would require resetting of the apparatus, due to changes in conditions of said doors and damper or in the connections 24, 27. It will be likewise evident that due to the action of the rock-shaft 16, and the transmission thereto of the movement of the piston-rod 6 through the slideable and pivotal joint 20, 21 the pressure regulator is rendered highly responsive to varying steam pressures in the boiler and is greatly conducive to very efficient operation of the regulator, since said rock-shaft is capable of imparting a large throw to the arms 23, 26 and thereby amplifies the comparatively small movement of the piston 5 to a much larger movement of the said doors and damper. The regulator has been thus found to be responsive with complete accuracy to controlling uniformly steam pressures as low as two pounds. It will be further evident that, if desired, the regulator may be operated to control the damper only, leaving the control of the ash-pit doors entirely optional with the user, in which case all that is required is removal of the arm 23 from the apparatus, by unthreading its set-screw 18^a.

Variations may be resorted to within the scope of the invention, and portions of the improvements may be used without others.

Having thus described my invention, I claim:

1. A pressure regulator for steam boilers having the combination with a cylinder, a piston therein actuated by the steam from the boiler, and connections joining the damper and air door of the boiler with the regulator, of a head for said cylinder secured thereto, a piston-rod passing through said head and guided thereby, a sleeve adjustable along said rod, means to secure said sleeve to the rod in any adjusted position, a cross-bar through which said rod is slideable, a spring located between said sleeve and said bar surrounding said rod, a pair of bolts secured to said head passing through said bar, nuts threading over said bolts bearing against said bar to regulate the pressure of said spring against said sleeve, a rock-shaft mounted upon said head, a lever extending from said shaft joined pivotally and slideably to said sleeve, arms extending from said shaft joined pivotally to said connections, and means to adjust the angularity of said arms relatively to said shaft.

2. A pressure regulator for steam boilers

- having the combination with a cylinder, a piston therein actuated by the steam from the boiler, and connections joining the damper and air door of the boiler with the regulator, of a head for said cylinder secured thereto, a piston-rod passing through said head and guided thereby, a member secured to said rod, a cross-bar through which said rod is slidale, a spring located between said member and said bar surrounding said rod, a pair of bolts secured to said head passing through said bar, nuts threading over said bolts bearing against said bar to regulate the pressure of said spring against said member, a rock-shaft mounted upon said head, a lever extending from said shaft joined pivotally and slidably to said member, and arms extending from said shaft joined pivotally to said connections. 10
3. A pressure regulator for steam boilers having the combination with a cylinder, a piston therein actuated by the steam from the boiler, and connections joining the damper and air door of the boiler with the regulator, of a head for said cylinder secured thereto, a piston-rod passing through said head and guided thereby, a member secured to said rod, a cross-bar through which said rod is slidale, a spring located between said member and said bar surrounding said rod, a pair of bolts secured to said head passing through said bar, nuts threading over said bolts bearing against said bar to regulate the pressure of said spring against said member, a rock-shaft mounted upon said head, a lever extending from said shaft joined pivotally and slidably to said member, and means to join said shaft with said connections. 20
4. A pressure regulator for steam boilers having the combination with a cylinder, a piston therein actuated by the steam from the boiler, and connections joining the damper and air door of the boiler with the regulator, of a head for said cylinder secured thereto, a piston-rod passing through said head and guided thereby, a member secured to said rod, a cross-bar through which said rod is slidale, a spring located between said member and said bar surrounding said rod, a pair of bolts secured to said head passing through said bar, nuts threading over said bolts bearing against said bar to regulate the pressure of said spring against said member, a rock-shaft mounted upon said head, means to transmit the movement of said member to said shaft, and means to join said shaft with said connections. 30
5. A pressure regulator for steam boilers having the combination with a cylinder, a piston therein actuated by the steam from the boiler, and connections joining the damper and air door of the boiler with the regulator, of a head for said cylinder secured thereto, a piston rod passing through said head and guided thereby, a member secured to said rod, a cross-bar through which said rod is slidale, a spring located between said member and said bar surrounding said rod, a pair of fixed bolts passing through said bar, nuts threading over said bolts bearing against said bar to regulate the pressure of said spring against said member, a rock-shaft mounted in fixed bearings, a lever fixed to said shaft joined pivotally and slidably to said sleeve, and means to transmit the actuation of said shaft to the damper and air doors of the boiler. 40
6. A pressure regulator for steam boilers having the combination with a cylinder, and a piston therein actuated by the steam from the boiler, of a piston rod, a sleeve adjustable along said rod, means to secure said sleeve to the rod in any adjusted position, a cross-bar through which said rod is slidale, a spring located between said sleeve and said bar surrounding said rod, a pair of fixed bolts passing through said bar, nuts threading over said bolts bearing against said sleeve to regulate the pressure of said spring against said sleeve, a rock-shaft mounted in fixed bearings, a lever fixed to said shaft joined pivotally and slidably to said sleeve, and means to transmit the actuation of said shaft to the damper and air doors of the boiler. 50
7. A pressure regulator for steam boilers having the combination with a cylinder, and a piston therein actuated by the steam from the boiler, of a piston rod, a member secured to said rod, a cross-bar through which said rod is slidale, a spring located between said member and said bar surrounding said rod, a pair of fixed bolts passing through said bar, nuts threading over said bolts bearing against said bar to regulate the pressure of said spring against said member, a rock-shaft mounted in fixed bearings, a lever fixed to said shaft joined pivotally and slidably to said member, and means to transmit the actuation of said shaft to the damper and air doors of the boiler. 60
8. A pressure regulator for steam boilers having the combination with a cylinder, and a piston therein actuated by the steam from the boiler, of a piston rod, a member secured to said rod, a cross-bar through which said rod is slidale, a spring located between said member and said bar surrounding said rod, a pair of fixed bolts passing through said bar, nuts threading over said bolts bearing against said bar to regulate the pressure of said spring against said member, a rock-shaft mounted in fixed bearings, means to transmit the movement of said member to said shaft, and means to transmit the actuation of said shaft to the damper and air doors of the boiler. 70
9. A pressure regulator for steam boilers having the combination with a cylinder, and a piston therein actuated by the steam from the boiler, of a piston rod, a sleeve adjustable along said rod, means to secure said sleeve to the rod in any adjusted position, a

cross-bar through which said rod is slidable, a spring located between said sleeve and said bar surrounding said rod, a pair of fixed bolts passing through said bar, nuts threading over said bolts bearing against said bar to regulate the pressure of said spring against said sleeve, and means to transmit the actuation of said sleeve to the damper of the boiler.

- 10 10. A pressure regulator for steam boilers having the combination with a cylinder, and a piston therein actuated by the steam from the boiler, of a piston rod, a member secured to said rod, a spring surrounding said rod bearing against said member, means co-operating with said rod to regulate the pressure of said spring against said member, a rock-shaft mounted in fixed bearings, means to transmit the movement of said member 15 to said shaft, and means to transmit the actuation of said shaft to the damper of the boiler.

- 11 11. A pressure regulator for steam boilers having the combination with a cylinder, and a piston therein actuated by the steam from the boiler, of a piston rod, a member secured to said rod, a spring surrounding

30 said rod bearing against said member, means movable along said rod co-operating therewith to regulate the pressure of said spring against said member, a rock-shaft mounted in fixed bearings, means to transmit the movement of said member to said shaft, and means to transmit the actuation of said shaft to the damper of the boiler.

35 12. A pressure regulator for steam boilers having the combination with a cylinder, and a piston therein actuated by the steam from the boiler, of a piston rod, a member adjustable along said rod, means to secure 40 said member to said rod in any adjusted position, a spring surrounding said rod bearing against said member, means movable along said rod co-operating therewith to regulate the pressure of said spring against 45 said member, a rock-shaft mounted in fixed bearings, means to transmit the movement of said member to said shaft, and means to transmit the actuation of said shaft to the damper of the boiler.

50 Signed at the city of New York, in the county of New York, and State of New York, this 3rd day of November, A. D. 1919.

ADOLF SCHOLZ.
